UNITED STATES PATENT OFFICE

BERNARD ROWNTREE, OF CARMEL HIGHLANDS, CALIFORNIA

SLIDING-DOOR HANGER

Application filed September 14, 1927. Serial No. 219,448.

This invention relates to sliding door hangers for elevators, garages, warehouses and the like, and has for its principal object the provision of rolling means for supporting sliding doors such that the same shall consist of as few parts as possible, with provisions for reducing friction so as to require a minimum of effort to open and close the door.

10 A further object of the invention is to provide a door hanger of such construction that when the door is displaced from the vertical plane or attempts to jump or tilt in the line of its travel it is prevented from leaving its track with the introduction of little or no additional friction. Thus whether the door be displaced longitudinally, transversely or both, from its normal position it will not jam but will move as easily as before its displacement. By virtue of the construction employed to accomplish this object of the invention it is not essential that the door be hung plumb from its supporting member or that the supporting member itself be installed 20 plumb on the wall of the building.

Further objects of the invention will be apparent and the invention itself will be better understood from the following description taken in connection with the accompanying drawings in which Fig. 1 is a side elevation of a door and its supporting structure showing the positions of two door hangers embodying the subject matter of this invention; Fig. 2 is a side elevation of a preferred form of the door hanger; Fig. 3 is a cross-sectional view of the hanger taken substantially on the line 3—3 of Fig. 2; Fig. 4 is a partial cross-sectional view of a modified form of the hanger; Fig. 5 is a side elevation view of a door hanger embodying another form of the invention; and Fig. 6 is a cross-sectional view taken substantially on the line 6—6 of Fig. 5.

Referring to Figs. 2 and 3, the numeral 1 indicates a door header or the side of the structure in connection with which the slideable door 2 is used. Just above the upper edge of the door 2 a channel member 3, which may be and preferably is in the form of a commercial channel iron, is bolted or otherwise

secured to the door header 1 by fastening means, not illustrated in the drawings, since they are well known in the art. The inner surface of the lower leg 4 of the channel member 3 has fastened thereto a track 5 55 preferably in the form of a half-round rod extending the length of the channel member 3 and securely fastened in position by means of the screws 6. The inner surface of the upper leg 7 of the channel member 3 is 60 grooved or recessed preferably along a cylindrical surface, the center of the radius of which coincides with the center line 8 of the track 5. A strap 9 is securely fastened to the upper portion of the door 2 by suitable means, such as the screws 10 illustrated in Figs. 2 and 3. A hub member 11 is positioned within a hole located in the upper end of the strap 9. Two substantially circular discs 12 and 13 are positioned on the hub member 11 as shown in Fig. 3, these discs being provided with upwardly projecting portions 14 and 15. A sheave or grooved wheel 16 is located between the spaced discs 12 and 13 and is adapted to rotate freely and 70 travel along the surface of the track 5. The sheave 16 rotates freely with respect to the hub member 11 by virtue of a plurality of bearing rolls 17 equally spaced about the hub member 11, between this member and the sheave 16. The rollers 17 are held in position by annular guides 18 in which the trunnions 19 of the bearing rolls 17 are free to rotate. A bearing ball 20 is preferably positioned between the projecting portions 14 and 15 in suitable recesses therein and, in the normal operation of the device, rolls freely over the upper surface of the sheave 16. If the door 2 is raised for any reason during the movement thereof the bearing ball 20 will likewise be raised and brought into contact with the curved recess in the channel leg 7. Since this ball 20 rotates in a direction corresponding to the direction in which the door is moving, little or no additional friction will be caused between the parts of the apparatus when the ball rotates in the cylindrical groove if the door 2 be raised above its normal position.

If the door 2 is displaced from the vertical 100

plane as it is being moved the hanger apparatus just described is free to turn about the line 8 of the track 5, the cylindrical recess in the leg 7 permitting the bearing ball 20 to be moved to one side or the other of the vertical position.

It will be readily understood that if for any reason the channel member 3 is fastened to the door header 1 so that its cross-sectional center line is not perpendicular to the plane 10 of the door 2, the apparatus will operate without any additional friction.

The manner of mounting the door hanger, described above, upon the hub 11 will be 15 obvious to one skilled in the art and need not be described herein. When the apparatus is thus mounted on the hub 11, the ends thereof may be upset, as indicated at 21, or otherwise provided with fastening means to 20 hold the various parts of the apparatus securely in position.

Referring to the modification of my invention illustrated in Fig. 4, it will be observed that in place of the bearing ball a roller 22 25 may be provided, which roller is mounted upon a shaft 23 supported by the projections 14 and 15 of the discs 12 and 13. The contour of the roller 22 is similar to that of the sheave 16 and it, therefore, rotates freely with the 30 sheave 16.

Referring now to Figs. 5 and 6 of the drawings, it will be seen that the strap 9 and the hub or central bearing shaft 11 are similar to those shown in Figs. 2 and 3. The semi-cylindrical track member 5 is also similar to 35 that of Fig. 3.

Upon the central bearing 11 two circular plates or discs 25 and 26 are mounted. These being small in diameter they are substantially 40 in the form of annuli. Upon the central portion of the central bearing or hub 11 anti-friction bearing rolls 27 are adapted to rotate. Adjacent the ends of the bearing rolls 27 are annular rings 28 and 29 having holes 45 therein through which pass the rotatable spacing members or rods 32. These rods or spacing members 32 are held in longitudinal position by the annular rings 25 and 26. The rolls 27 are preferably provided with trunnions 27' which are rotatably supported in 50 the annular rings 28 and 29. The annular grooved wheel or ring 24 rotates upon and in contact with the bearing rolls 27, and is also held in position on each side by a second set 55 of annular rings 30 and 31, the inner margins of which rest upon the spacing members 32 and are located between the annular rings 25 and 28 and the rings 26 and 29 respectively.

From the above description of Figs. 5 and 6, it will be seen that the hanger and its bearing wheel operate in substantially the same manner as previously described in connection 60 with Figs. 2 and 3. It will be noted, however, that no bearing ball is provided between 65 the upper leg 7 and the wheel 24. Instead of

the bearing ball the annular rings 30 and 31 are provided with arcuate outer margins which are adapted to roll along the under surface of the channel leg 7, which surface is recessed as described above.

In each of the modifications described and illustrated herein it will be noted that the uppermost bearing member, viz. the bearing ball or roller or the annular rings, which is adapted to contact with the under surface of the channel leg rolls in the direction of normal rolling upon this surface. Thus if the door lifts off its track this movement is limited by the bearing member contacting with this surface in such a way that little or no additional friction is introduced. In all of the forms described it will be noted that the friction between the parts is not increased by a displacement of the door slightly out of its vertical plane, and at the same time the hanger is extremely reliable in its action and free from the tendency to jump from its guiding track under any condition to which the vehicle or device on which it is placed may be subjected.

Having thus described these forms of my invention I wish it to be understood that various changes may be made by those skilled in the art without departing from the spirit and scope of my invention.

What I claim and desire to protect by Letters Patent is:—

1. A sliding door support of the type described comprising a horizontally extending trackway, a sheave adapted to roll upon said trackway, a door support carried by said sheave, a second trackway having a concave curved surface spaced parallel with and adjacent said first trackway, and an anti-friction means adapted to contact with said sheave and said second trackway and prevent excessive tilting and friction should the sheave be raised from its trackway by reason of a tilting of the door in sliding same.

2. A sliding door support of the type described comprising a horizontally extending trackway, a sheave adapted to roll upon said trackway, a door support carried by said sheave, a second trackway spaced above and overhanging said first trackway, the surface of said second trackway conforming to an arc struck from a point within said first trackway and an anti-friction means in rolling contact with said sheave carried by said door support adapted to contact with said second trackway and prevent excessive tilting and friction should the sheave be raised from its trackway by reason of a tilting of the door in sliding same.

3. A sliding door support of the type described comprising a horizontally extending trackway, a sheave adapted to roll upon said trackway, a door support carried by said sheave, a second trackway spaced above and overhanging said first trackway, said second

trackway having a surface spaced uniformly from the center of lateral swing of the door, and an anti-friction means interposed between the top of said sheave and said second trackway and carried by said door support adapted to contact with said second trackway and prevent excessive tilting and friction should the sheave be raised from its trackway by reason of a tilting or swinging of the door in sliding same.

10 4. In a door hanger of the character described, a door-supporting member, a shaft secured thereto, a bearing wheel rotatable with relation to the shaft, anti-friction rolls between said shaft and wheel, annular guides surrounding said shaft for holding said rolls in position, said guides having holes formed therein, trunnions carried by said anti-friction rolls and journaled in said holes whereby said rolls will be maintained in spaced relation with each other, and a pair of disks disposed on opposite sides of said wheel for maintaining alignment of said rolls and wheel.

25 5. In a sliding door hanger, a lower track having a convex curved surface, an upper track facing the same and having a concave surface substantially parallel to the surface of said lower track, a sheave having a surface 30 conforming in shape to the surface of said lower track and having rolling contact therewith, and a rotatable member for contacting with said upper track to prevent the sheave from leaving the lower track.
